UNITED STATES PATENT OFFICE.

JOHN DE WITT, OF WASHINGTON, DISTRICT OF COLUMBIA.

DESIGN FOR A CAR-BODY.

SPECIFICATION forming part of Design No. 22,759, dated August 29, 1893.

Application filed December 15, 1892. Serial No. 455,312. Term of patent 14 years.

To all whom it may concern:

Be it known that I, JOHN DE WITT, a citizen of the United States, and a resident of Washington, in the District of Columbia, have invented and produced a new and original Design for a Car-Body, of which the following is a specification, reference being had to the accompanying drawing, which is a perspective view of my new design.

10 The leading feature of my design consists in a car body 1, having platforms 2 and 3, one elevated above the other, and carrying each a number of transversely arranged seats 7. Projecting from the front is a series of platforms 4, 5, and 6, occupying a lower plane than the platforms 2 and 3, and carrying the transversely arranged seats 7. Arranged along the sides of the platforms 2, 3, 4, 5, and

15

6 are longitudinal horizontal platforms 8, 9, 10, and 11, and seats 12, 13, 14 and 15, and 20 contiguous to a number of each of the latter seats are steps 17, at the end of the car and to the front platform. The top of the car and the rear platform 18 are connected by means of a curved stairway 16. 25

Having thus fully described my invention, what I claim is—

The design for a car body, substantially shown and described.

In testimony wherof I hereunto affix my 30 signature in the presence of two witnesses.

JOHN DE WITT.
